UNITED STATES PATENT OFFICE.

UBALD HEBERT, OF MANCHESTER, NEW HAMPSHIRE, ASSIGNOR, BY MESNE ASSIGNMENTS, TO DRAPER CORPORATION, OF HOPEDALE, MASSACHUSETTS, A CORPORATION OF MAINE.

AUTOMATIC FILLING-REPLENISHING LOOM.

1,218,256.

Specification of Letters Patent.

Patented Mar. 6, 1917.

Application filed February 7, 1916. Serial No. 76,790.

To all whom it may concern:

Be it known that I, UBALD HEBERT, a citizen of the United States, and resident of Manchester, county of Hillsborough, State 5 of New Hampshire, have invented an Improvement in Automatic Filling-Replenishing Looms, of which the following description, in connection with the accompanying drawing, is a specification, like characters 10 on the drawing representing like parts.

This invention relates to improvements in filling replenishing looms in which a supply of filling carriers is maintained in a hopper from which the filling carriers are 15 transferred successively to the running shuttle by a suitable transerrer, and one object of the invention is to provide means to secure the proper position of the filling carrier during transfer in order that it may be 20 directed into the shuttle in proper position.

The invention in its more specific form relates to a filling replenishing loom of the well known Northrop type in which an intermittently rotatable hopper is employed 25 carrying a series of filling carriers about its periphery.

More particularly the invention relates to filling replenishing looms making use of filling carriers having feeling slots in the bar- 30 rel thereof such as are illustrated for example in the patents to William Parker Straw No. 906,748 granted December 15, 1908, No. 1,053,673 granted February 18, 1913, and No. 1,092,959 granted April 14, 35 1914. When this type of filling carrier is employed it is necessary that the slot there- in shall be positioned in a definite relation to the feeler in order that the latter may work properly. Consequently the butts of 40 the filling carriers are provided with suitable positioning means, usually slabbed or flattened surfaces generally in planes at right angles to the longitudinal planes of the slot, and these surfaces are engaged by 45 suitable jaws within the shuttle to retain the filling carriers in position. The filling carriers are carried in the hopper and fed therefrom by the transerrer as upon the call for filling replenishment, but when a 50 filling carrier is forced from the hopper toward the shuttle it frequently rotates more or less and is not infrequently driven into

the shuttle jaws in improper position. As a result the feeler fails to operate or a smash is caused.

Heretofore it has been proposed as in the patent to Alonzo E. Rhoades No. 1,167,363 granted January 4, 1916 to provide a vertically movable device which shall seize the positioning faces of the filling carrier and move down with the filling carrier maintaining it in position until it is forced into the shuttle.

The present invention provides guiding means which are fixed against vertical movement but which move rearwardly and forwardly and which engage with the filling carrier and prevent rotation of the filling carrier during transfer. By reason of this engagement as the filling carrier moves 70 downwardly during transfer and thus moves downwardly with respect to the guiding means the filling carrier is held against rotation while at the same time the guiding means moves rearwardly concurrently with 75 the lay thus enabling the filling carrier readily to be directed into the shuttle in proper position.

This invention is not limited to the particular construction illustrated and is 80 broadly directed to a guiding means for the filling carrier during transfer wherein the filling carrier moves with respect to the guiding means while it is being guided thereby, as contra-distinguished from such 85 a construction as shown in the aforesaid Rhoades patent where the guiding means during transfer moves downwardly with the filling carrier. In its broader features the invention therefore includes within its 90 scope other forms devised by me and made the subject of separate applications as for example my application No. 107,247 filed July 3, 1916 for automatic filling replenishing looms, and my application No. 107,248 95 filed July 3, 1916 for automatic filling replenishing looms.

This invention in its more specific features involves a guide for the filling carrier during transfer which moves rectilin- 100 early between the hopper and the shuttle and is given a positive movement rearwardly by being connected to the transerrer so as thus to move concurrently with the lay.

The invention further and more specifically comprises a guiding means in which the filling carrier is not only positioned rotarily but longitudinally and in its still 5 more specific form by a yielding member engaging the rings of the filling carrier.

While this invention is disclosed herein as being applied to bobbins having feeling slots or recesses in the barrels thereof, it 10 will be understood that it is also adapted for positioning the usual bobbins in looms and is therefore of universal adaptation to filling replenishing looms.

The nature of the invention will more 15 fully appear from the accompanying description and drawings and will be particularly pointed out in the claims.

The drawings show so much of an ordinary automatic filling replenishing loom as 20 is necessary to illustrate in connection therewith the improvements in mechanism which constitute one of the preferred forms of my invention.

In the drawings;

25 Figure 1 is a right hand side elevation and partial transverse section of a portion of an automatic filling replenishing loom of the Northrop type with the parts involved in this invention applied thereto,

30 Fig. 2 is a detail plan view of the guide and positioning means which constitute the novel feature of my invention showing also in cross section a portion of the link for actuating the same,

35 Fig. 3 is a vertical sectional view in a plane at the forward edge of the main portion of the guide.

The construction of the loom illustrated herein and to which a preferred form of the 40 invention is applied is of the type illustrated and described at length in the patent to Stimpson and Southwick No. 823,644 granted June 19, 1906, and in view thereof and of the well known character of the Northrop 45 loom it would be unnecessary to describe the general construction of the loom other than such parts as are immediately related to the present invention.

The loom comprises the usual breast beam 50 1 to which is secured a stand 2 supporting the usual rotatable hopper or battery 3 which comprises two connected disks or plates to receive, hold and position separate filling carriers. Where filling carriers having slotted butts are utilized, the slots 4 in the periphery of the disk 3 are of just a sufficient width to embrace the slotted ends of the filling carriers. The plate 3 is rotatably mounted upon a shaft 5 and is connected to 55 the opposite disk, not shown, by a sleeve 6 which is provided with recesses to receive the tips of the filling carriers.

The filling carriers or bobbins are advanced one by one into position for transfer to the shuttle by any usual ratchet mech-

anism such as that illustrated in the patent to Stimpson and Southwick above referred to, which is not shown herein.

The filling replenishing mechanism comprises the usual transfer arm 7 having a hammer head 8 which preferably is cut away at 9 for purposes which will hereinafter be described, the arm 7 being a portion of the bell crank lever which is pivotally mounted upon a stud 10 projecting from the hopper 75 stand 2. The other arm 11 of the bell crank lever is connected by a pivot 12 to the usual dog 13 which when transfer is called for is adapted to be engaged by the bunter 14 on the lay 15.

80 The lay is carried by the usual sword 16 and supports the shuttle box 17 which receives the shuttle 18.

Heretofore an abutment has been carried, either rigidly or yieldably by the hopper 85 stand to arrest the filling carriers in the proper position in relation to the boxed shuttle and such abutments are generally found to be effective when the usual bobbins are employed, unless, as is sometimes the case, the 90 bobbin is slightly shorter than the standard size to which the loom is adapted.

In looms however in which bobbins having slotted barrels are used it is found that the bobbin is rotated slightly by the engagement of the transfer arm and the guiding means so that when it reaches the shuttle the slotted faces are not properly positioned in respect to the shuttle jaws.

95 In the construction illustrated a movable 100 guiding means is interposed between the hopper and the boxed shuttle which is adapted to position and guide the bobbin or filling carrier almost directly into the shuttle jaws, being so constructed as to hold the bobbin 105 against rotation until it is thrust into the shuttle. In order to provide for the proper coöperation between the transfer arm and the shuttle as it is brought into transfer position by the lay, means are provided for 110 moving the guide concurrently with the movement of the lay and so that the coöperation of these parts will be properly timed to effect the result above described.

115 The preferred form of guide which is illustrated in the accompanying drawings comprises a plate 20 having preferably integral extensions 21, 22 slidably mounted upon ledges 23, 24 carried by the hopper stand, the extensions 21, 22 being desirably provided with slots 25 to receive screws 26 seated in the extensions 23, 24 and having enlarged heads to retain the plate 20 slidably in position upon its supports. The central portion of the plate 20 is provided with a 125 downwardly extending boss 27 which has an offset portion 28.

120 The boss and the offset portions are vertically apertured to receive the butt of the bobbin, the offset portion having a recess 29 130

with parallel walls adapted to engage the slabbed faces of the bobbin butts and the forward portion of the recess being enlarged and provided at one side with grooves 30, 5 to receive the rings upon the bobbin and at the opposite side with a cut away portion forming a recess for a yielding member 31 which desirably is in the form of a plate mounted upon a pivot 32 carried by ears 10 33, 34, extending upwardly from said plate 20, the plate 31 being preferably provided with a flange 35 adapted to engage the side of the ring upon the bobbin butt which is nearest to the barrel of the bobbin so as to 15 force the bobbin longitudinally into its place in the guide, if by chance it is slightly out of alignment.

The member 31 is preferably held in forward position by a spring 36 which at one 20 end bears against the said plate and at the other end bears against the side of the ledge 23 of the hopper stand.

In order to limit the forward movement of the plate 31 it is desirably provided with 25 an integral downwardly extending tail 38 upon the opposite side of its pivot, said tail engaging the side of a web 39 which extends upwardly from the guide 20 between the ears 33, 34.

30 By this construction the spring 36 is adapted to perform the double function of maintaining the yielding member 31 normally in advanced position and also of restoring the guide as a whole to its normal 35 position when permitted to return after transfer has been effected.

As the transfer from the hopper to the shuttle must be effected with exceeding rapidity it is found necessary, or at least 40 desirable, that the guide move concurrently with the lay as the latter approaches transfer position. In the present case such movement is provided by causing the transfer arm to move the guide simultaneously with 45 the transfer head.

A preferred embodiment for accomplishing this purpose comprises a link 40 pivotally connected to a stud 41 on the arm 11 of the transferrer, said link 40 having at its 50 opposite end a slot 42 adapted to receive a stud 43 extending laterally from an arm 44 on the extension 21. When transfer is called for in the operation of the loom the dog 13 is raised into the path of the bunter 14 in 55 the usual way, whereupon the further movement of the lay rocks the transfer arm upon its pivot so that the head 8 engages the butt of the bobbin and thrusts the same first into the guide and upon further movement into 60 the jaws of the shuttle in the following manner.

The pin and slot connection between the link 40 and the guide 20 provides for an initial movement of the transferrer so that 65 the head 8 may engage the butt of the bob-

bin and thrust the same into the aperture of the guide 20. At this time the stud 43 will engage the outer end of the slot 42 and further movement of the transfer arm will cause the movement of the guide in the 70 same direction concurrently with the movement of the lay so that as the head 8 of the transferrer arm descends farther the bobbin will be thrust into the shuttle.

In order to avoid interference between 75 the guide in its movement and the descending transfer arm the latter is cut away at 9 sufficiently to permit the guide to reach the limit of its throw without striking the end of the transfer arm. 80

After transfer has been effected and the lay moves in the opposite direction the spring 36 forces the guide into its normal position in the manner above described.

While I have illustrated herein a preferred embodiment of my invention various modifications thereof may be made within the scope and spirit of the invention as covered by the following claims. 85

Having thus described my invention what 90 I claim as new and desire to secure by Letters Patent is:

1. A filling replenishing loom comprising a hopper adapted to contain a plurality of filling carriers, a transferrer and means for 95 actuating the same, and rearwardly and forwardly movable guiding means fixed against vertical bodily movement and acting to engage with and prevent rotation of a filling carrier with respect to said guiding means 100 during transfer whereby the filling carrier will be delivered to the shuttle in predetermined rotary position.

2. A filling replenishing loom comprising a hopper adapted to contain a plurality of 105 filling carriers, a transferrer and means for actuating the same, a rearwardly and forwardly movable guide acting to engage with and prevent rotation of a filling carrier during transfer, and means for permitting rearward movement of said guide concurrently 110 with the lay during transfer whereby the filling carrier will be delivered to the shuttle in predetermined rotary position.

3. A filling replenishing loom comprising 115 a hopper adapted to contain a plurality of filling carriers, a transferrer and means for actuating the same, a rearwardly and forwardly movable guide fixed against vertical bodily movement and acting to engage with and prevent rotation of a filling carrier during transfer, and means for permitting rearward movement of said guide concurrently 120 with the lay during transfer whereby the filling carrier will be delivered to the shuttle 125 in predetermined rotary position.

4. A filling replenishing loom comprising a hopper adapted to contain a plurality of filling carriers, a transferrer and means for 130 actuating the same, a rearwardly and for-

wardly movable guide fixed against vertical bodily movement and acting to engage with and prevent rotation of a filling carrier during transfer, means for yieldingly maintaining said guide in forward position and permitting rearward movement of said guide concurrently with the lay during transfer whereby the filling carrier will be delivered to the shuttle in predetermined rotary position.

10 5. A filling replenishing loom comprising an intermittently rotatable hopper adapted to contain a plurality of filling carriers having butts provided with positioning means, 15 a transerrer and means for actuating the same and a rearwardly and forwardly movable guiding means fixed against vertical bodily movement and acting to coöperate with said positioning means and thereby 20 prevent rotation of a filling carrier during transfer whereby the filling carrier will be delivered to the shuttle in predetermined rotary position.

25 6. A filling replenishing loom comprising an intermittently rotatable hopper adapted to contain a plurality of filling carriers, a transerrer and means for actuating the same, a rearwardly and forwardly movable guide fixed against vertical bodily movement, and coöoperating guiding faces on said 30 guide and on said filling carriers acting to engage with each other and prevent rotation of the filling carrier during transfer.

35 7. A filling replenishing loom comprising a hopper adapted to contain a plurality of filling carriers, a transerrer and means for actuating the same, a movable guide intermediate of said hopper and the shuttle and means for reciprocating the same concurrently 40 with the movement of the lay and the transerrer whereby the filling carrier will be properly positioned in said guide before it enters the shuttle and will be delivered directly into the jaws of the shuttle therefrom.

45 8. A filling replenishing loom comprising an intermittently rotatable hopper adapted to contain a plurality of filling carriers, a transerrer and means for actuating the same, a movable guide intermediate of said hopper and the shuttle and means yieldably 50 connected to said transerrer for reciprocating the guide concurrently with the movement of the lay whereby the filling carrier will be properly positioned in said guide and 55 thrust directly therefrom into the shuttle.

60 9. A filling replenishing loom comprising an intermittently operable hopper adapted to receive and position a plurality of filling carriers having slabbed butts, a transerrer and 65 means for actuating the same, a guide intermediate of said hopper and the shuttle having a guideway for the slabbed butts of the filling carrier and coöperating relatively yieldable guides to engage the filling carrier rings whereby a filling carrier will be

properly positioned both longitudinally and rotarily before it is thrust into the shuttle.

10 5. A filling replenishing loom comprising an intermittently operated hopper adapted to receive a plurality of filling carriers having slabbed butts, a transerrer and means for actuating the same, positioning means intermediate of said hopper and the positioned shuttle having means to engage the slabbed butts of the filling carriers and a yieldable member to engage the filling carrier rings whereby the filling carrier will be properly positioned both longitudinally and rotarily in said guide before it is thrust into the shuttle.

15 11. A filling replenishing loom comprising an intermittently movable hopper having peripheral recesses adapted to receive slabbed butts of filling carriers, a transerrer and means for actuating the same, a movable 20 guide intermediate of said hopper and the shuttle having a guideway for the slabbed butts of the filling carriers and coöperating members adapted to engage the rings of the filling carriers consisting of a grooved member and a coöperating spring actuated flanged member whereby the filling carrier will be positioned properly both rotarily and longitudinally before it is thrust into the 25 jaws of the shuttle.

30 12. A filling replenishing loom comprising an intermittently movable hopper adapted to contain a plurality of filling carriers, a transerrer and means for actuating the same, guiding means intermediate of said 35 hopper and the shuttle consisting of a reciprocable member having coöperating relatively yielding guiding instrumentalities and means for yieldably connecting said sliding member to said transerrer whereby the 40 actuation of the latter will cause the reciprocation of the guiding means concurrently with the movement of the lay as it approaches transfer position.

45 13. A filling replenishing loom comprising a hopper adapted to contain a plurality of filling carriers, a transerrer and means for actuating the same, a guide intermediate of said hopper and the shuttle consisting of a sliding member operatively attached to said transerrer and having coöperating guiding members to receive and position the butts of filling carriers, one of said members being yieldable and a spring between said yieldable member and the hopper stand adapted to restore the guiding member to normal 50 position.

55 14. A filling replenishing loom comprising an intermittently rotatable hopper adapted to receive a plurality of filling carriers, having slabbed butts, a transerrer and means for actuating the same, a guide intermediate of said hopper and the shuttle consisting of a slotted member having a guideway to receive the slabbed butts of the filling carriers,

a grooved guide for the filling carrier rings, a coöperating pivotally mounted flanged plate, a spring abutting against said plate and the hopper stand and a pin and slot connection between said transerrer and said guide whereby the transerrer is permitted an initial movement independent of the guide but will thereafter cause the guide to move concurrently with the movement of

10 the lay.

15. A filling replenishing loom comprising a hopper adapted to contain a plurality of filling carriers, a transerrer and means for actuating the same, a reciprocable guide intermediate of said hopper and the shuttle having coöperating members for engaging

the butts of the filling carrier, one of said members being yieldable, a spring bearing at one end against said yieldable member and at the opposite end against a relatively stationary member, means operably connected to the transerrer for moving said reciprocable guide in one direction and for permitting the spring to move the yielding member and therethrough the reciprocable guide in 25 the opposite direction, whereby said spring serves both to actuate the yieldable ring engaging member and the reciprocable guide.

In testimony whereof, I have signed my name to this specification.

UBALD HEBERT.
